ELECTRIC TERMINAL

John E. Carlson, Forestville, Conn., assignor to
The Trumbull Electric Manufacturing Company,
Plainville, Conn., a corporation of Connecticut

Application December 22, 1937, Serial No. 181,062

3 Claims. (Cl. 173—259)

The main object is to provide a device which will securely hold wires of various sizes. I have especially sought to provide a form which will accommodate either a single wire or two or more wires. Another object is to provide a device which will simultaneously accommodate two or more wires of different sizes.

Another object is to provide a device with which a maximum clamping effect can be produced with a minimum effort.

Another object is to provide a terminal of the character described which can be used to secure either a solid or a stranded wire or a solid wire and one or more stranded wires.

15 The preferred form as shown in the accompanying drawing includes a base plate, a tilting clamp plate, a screw or a screw threaded post and a clamp nut. The clamp plate is loosely mounted on the screw and has a projecting central rib against which the clamp nut presses so as to force the clamp plate toward the base plate and grip one or two wires beneath the edges of the clamp plate.

Fig. 1 is a plan view showing the invention as applied to one form of a connector.

25 Fig. 2 is an end view of the same, the dot-dash lines suggesting a plurality of positions for terminals.

Fig. 3 is a fragmentary sectional view showing 30 a single terminal with one wire in place.

Fig. 4 is an enlarged elevation of a terminal with two wires of different sizes clamped in place.

Fig. 5 is a similar elevation with only one wire 35 in place.

Fig. 6 is a plan view showing the clamping plate mounted on a base plate, with the screw in section.

Fig. 7 is a perspective view of a clamping plate.

40 Fig. 8 is a side view of the clamping parts.

The four metal parts are the screw post 10, the base plate 11, the clamping plate 12 and the nut 13. The screw post may be mounted on an 45 insulating base 14 for instance of a connector or other electrical device.

The screw 10 is threaded into the base plate 11 so as to hold it in place. The clamp plate has a hole 15 considerably larger than the screw 50 so as to permit the plate to tilt freely on the screw. Along the center of the plate 12 is a rib 16 which projects considerably beyond the general plane of the plate. The lower face 17 of the nut 13 is flat so as to engage the top of 55 the rib of the clamp plate along a central line

thus allowing the clamp plate to tilt or rock along this central line like on a knife edge to clamp the wire or wires.

Beneath the opposite edges of the clamping plate preferably are grooves 18 and 19 adapted 5 to position and hold different sizes of wires such as 20, 21 and 22.

The clamping plate may also have shoulders 23 and 24 on opposite sides which may serve to limit the tilting action of the plate and to coact 10 with the central rib 16 in some instances so as to provide an additional seat for the nut 13 when the plate 11 is tilted in its rocking engagement with the wire or wires. The central rib 16, however, projects above the level of the shoulders 23 15 and 24 so as to permit a considerable tilting of the plate.

The support 14 in this case has projecting walls 25 and 26 between which is the channel 26 in which the terminal is mounted. These 20 walls serve to assist in positioning and confining the clamp plate and base plate or terminal 11 between the adjacent side walls.

The base plate 11 and the clamping plate 12 are positioned some distance from the edge of 25 the insulating base or support 14 so that the insulation on the wires may be butted against the clamp plate and thus all of the stripped portion of the wires may be confined between the walls 30 of the insulating base.

The knife-edge contact between the nut and the crown of the rib of the clamping plate makes it easy to turn the nut when clamping the wire or wires and to centralize the pressure of the nut. It also limits the maximum tilting of the clamp 35 plate.

In practice the wires to be attached are bared or skinned at their ends for a distance about equal to the width of the clamping plates. The nut is then loosened and the wires are inserted 40 with the insulation of the wires abutting the ends of the plates and the nuts are then tightened up to secure the wires in position. It is general practice to use stranded wires and in some instances a single line wire may be used in 45 connection with two or more branch wires and in such instances the form of clamp described herein adapts itself to such conditions by squeezing or compressing the wires so that the nut not only bears directly upon the central rib but also 50 upon one of the shoulders 23 or 24 so as to more effectively clamp the multiple number of wires.

In practice the clamping plate may be designed so that when only one wire of a certain large size is to be used, the nut will engage and bear 55

upon not only the central rib of the clamp plate but also upon one of the shoulders 23 or 24 and the opposite edge of the plate will bear upon the base plate 11 thus providing a very efficient 5 clamp for the wire. This condition is clearly shown in Fig. 5 of the drawing.

I claim:

1. A binding post including a stationary base plate having a screw threaded post projecting rigidly therefrom, a clamp plate loosely mounted on said post so as to permit it to tilt, said clamp plate having a central rib and a somewhat lower rib at each of the opposite sides of the central rib, said side ribs being spaced apart and having 15 grooves under the side ribs at opposite sides of the post with their inner edges substantially tangent to the sides of the post for forcing conductor wires against the sides of the post and a clamp nut having a base portion of greater diameter than the distance between the tops of the side ribs so that the base portion of said clamp 20 nut can bear upon the top portion of the central rib of the clamp plate and also upon the top portion of one of the side ribs when a wire conductor 25 is located beneath one side of the clamp plate and the clamp plate is tilted and force the wire or wires against the base plate and the post.

2. An electric terminal having a stationary base plate, a screw threaded post extending rigidly therefrom, a clamp plate loosely mounted so

as to tilt on the post, said plate having a central projecting rib on the top and with shoulders on opposite sides of the central rib but much lower than the central rib with grooves beneath the shoulders adjacent the post and a 5 clamp nut adjustable on the post and having its inner face coacting with the rib of the plate and with one of the shoulders to force the plate to grip one or more wires and force the same simultaneously against the post and the base plate. 10

3. An electrical connector including an insulating base having a channel with insulating confining walls, a wire connector mounted within the channel and including a base plate, a post projecting therefrom, a tilting clamping plate 15 on said post having a central perforation considerably larger in diameter than said post and having a central rib projecting from the remainder of the clamping plate and two side ribs with grooves beneath them adjacent the post 20 and means for engaging the central rib and one of the side ribs of the clamping plate within the channel for forcing one or more wires of different diameters under the clamping plate against said post, the side edges of the clamping plate 25 extending close to the insulating confining walls of the channel and preventing the sidewise escape of wires held in said grooves.

JOHN E. CARLSON. 30
